UNITED STATES PATENT OFFICE.

HARRIET R. ETHERIDGE, OF JACKSON, MICHIGAN.

TOBACCO BOX.

Application filed July 13, 1923. Serial No. 651,381.

To all whom it may concern:

Be it known that I, HARRIET R. ETHERIDGE, a subject of the King of Great Britain, residing at Jackson, in the county of Jackson 5 and State of Michigan, have invented new and useful Improvements in Tobacco Boxes, of which the following is a specification.

This invention relates to special receptacles and packages and has for its object 10 the provision of a novel can or box for tobacco intended to be used as the original package in which tobacco may be put up and sold, the can being provided with means for holding a packet of cigarette papers 15 and also pipe cleaners and being furthermore provided with a discharge spout which will facilitate pouring out of the tobacco into a pipe or onto a cigarette paper.

An important and more specific object is 20 the provision of a receptacle of this character in which the cigarette papers are carried by a slide normally contained within an enclosure but automatically moved into exposed position when the spout is moved into 25 its active position.

Another object is the provision of a device of this character which will be very attractive in appearance, which will be highly advantageous as an advertising 30 novelty and which will be a general improvement in the art.

With the above and other objects and advantages in view the invention consists in the details of construction to be hereinafter 35 more fully described and claimed and illustrated in the accompanying drawings, in which:

Figure 1 is a perspective view of the can showing it in normal or closed position,

40 Figure 2 is a similar view showing the spout swung into its operative position and the packet of cigarette papers exposed,

Figure 3 is a horizontal cross section through the box,

45 Figure 4 is a vertical cross section taken through the slide,

Figure 5 is a vertical longitudinal section looking toward that side of the can which carries the slide,

50 Figure 6 is a perspective view of the slide removed, and

Figure 7 is a perspective view of the spout member removed.

55 Figure 8 is a perspective view of the slide housing removed.

Referring more particularly to the drawings I have shown the can 10 constructed in most respects like other cans for this purpose, that is to say it consists of the usual can body of ordinary size, shape, material and finish and provided with the usual hinged cover 11 which permits filling with tobacco. In carrying out my invention I provide, upon one side of the box or can a guide or housing 12 formed of sheet metal 60 and of a size slightly larger than a packet of cigarette papers indicated at A. This guide might be secured in place in various different ways, though I have shown it as provided at its corners with small tongues 65 13 which are passed through slots 14 in the side of the can and subsequently clinched. One edge of this guide is formed with a rolled flange 15 for the purpose of holding 70 a pipe cleaner indicated at B.

Movably mounted within the guide 12 is a slide 16 formed at both ends with retaining flanges 17 for holding the packet of cigarette papers, and the upper end is formed with a small cut out portion 18 75 80 for the insertion of a finger whereby to facilitate removal of paper from the packet. Carried by the rear side of this slide is a wire or other loop 19 which projects through an elongated slot 20 in the side of the can. 85

One edge of the can or box is provided near the hinged cover with an opening 21 within which is located a spout 22 hinged at 23 at the lower edge 90 of the opening and having its upper edge 95 formed with a slightly outwardly curved lip 24 which is readily engageable by a thumb or finger nail to pull the spout into the operative position. This spout is formed of sheet metal and is U-shaped in cross section so as to have side arm portions 25 and 26 which bear against the inner faces of the sides of the can for preventing leakage of the tobacco. The arm 26 is prolonged or formed with an extension 100 27 engaged within the loop 19.

In actual use, the can is filled by the packer through the open top, the cover is then closed and the revenue stamp is applied in the usual manner. It is of course understood that the pipe cleaner and cigarette papers are inserted by the manufacturer or packer before the cover is closed. The purchaser need not necessarily open the cover 11 but must tear the stamp at the 105 110

spout to permit opening thereof. Of course if it is desired the cover may be opened for the purpose of giving access to the interior for loosening the tobacco, which is ordinarily packed tightly so that it may be subsequently shaken from the spout. When the user swings the spout into its open position as shown in Figure 2, the extension 27 of the arm 26 operates to move 10 the slide 16 upwardly so that the packet of papers will be projected from and will extend beyond the top of the guide 12 in convenient position to be grasped so that one may be removed for the purpose of 15 rolling a cigarette. When the spout is re-closed the extension 27 moves the slide 16 into the guide so that the papers are at all times protected against rumpling or soiling in the pocket.

20 From the foregoing description and a study of the drawings it will be apparent that I have thus provided a simply constructed and consequently inexpensive tobacco can or box which is well adapted for 25 advertising purposes and which may be used to great advantage by packers or manufacturers of tobacco, or which may also be constructed and used as a dispensing device which may be filled from an ordinary tobacco container, there being no restriction 30 whatever as to the mode of use.

While I have shown and described the preferred embodiment of the invention it is of course to be understood that I reserve 35 the right to make such changes in the form, construction and arrangement of parts as will not depart from the spirit of the in-

vention or the scope of the subjoined claims.

I claim:

1. In a tobacco box, a guide mounted 40 upon one side thereof, a slide movably mounted therein and formed for holding a packet of cigarette papers, a movable discharge member, and a connection between said discharge member and said slide whereby to move the latter to expose the papers when the discharge member is moved to operative position.

2. In a tobacco can, a guide mounted upon 45 one side thereof, a slide movably mounted therein and formed to hold a packet of cigarette papers, a discharge spout pivotally mounted upon one edge of the can and normally closing an opening therein, and an operative connection between said spout and 50 said slide whereby to move the latter into projected position when the spout is swung into operative position.

3. In a tobacco can, an enclosing guide 55 mounted upon one side thereof, a slide movably mounted within the guide and provided with means for retaining a packet of cigarette papers, the slide being normally contained within the guide, one edge of the can being formed near its top with an opening, 60 a discharge spout hinged at one edge of the opening and normally closing the same, an arm on said spout, a loop projecting from said slide into the can, the can being formed with a slot permitting movement of the loop 65 and said arm passing through said loop.

In testimony whereof I affix my signature.

HARRIET R. ETHERIDGE.
